UNITED STATES PATENT OFFICE

139,433

DESIGN FOR A COMBINED PERFUME BOTTLE AND STOPPER OR SIMILAR ARTICLE

John D. Buckingham, Chicago, Ill., assignor to
Lucien Lelong, Inc., Chicago, Ill., a corporation
of Illinois

Application August 17, 1944, Serial No. 114,913

Term of patent 14 years

(Cl. D58—6)

To all whom it may concern:

Be it known that I, John D. Buckingham, a citizen of the United States and a resident of the city of Chicago, in the county of Cook and State of Illinois, have invented a new, original, and ornamental Design for a Combined Perfume Bottle and Stopper or Similar Article, of which the following is a specification, reference being had to the accompanying drawing forming a part thereof.

On the drawing:

Figure 1 is a front elevational view of a com-

bined perfume bottle and stopper or similar article, showing my new design;

Figures 2, 3 and 4 are side and rear views thereof, with the stopper removed;

Figure 5 is a top plan view of the bottle and stopper; and

Figure 6 is a bottom plan view of the bottle.

I claim:

The ornamental design for a combined perfume bottle and stopper, or similar article, as shown.

JOHN D. BUCKINGHAM.
